US0D1022694S

(12) **United States Design Patent** (10) **Patent No.:** **US D1,022,694 S**
(45) **Date of Patent:** **** Apr. 16, 2024**

(54) **CONTAINER INSERT**

(71) Applicant: **The Topps Company, Inc.**, New York, NY (US)

(72) Inventors: **Elizabeth Mangold**, Santa Monica, CA (US); **Ashley Leinweber**, New York, NY (US); **Jason Reinbold**, Jersey City, NJ (US); **Anthony Trani**, Brooklyn, NY (US); **Bennet Otto Poepping**, Tuckahoe, NY (US); **David Block**, Brooklyn, NY (US)

(73) Assignee: **THE BAZOOKA COMPANIES, LLC**, New York, NY (US)

(**) Term: **15 Years**

(21) Appl. No.: **29/785,097**

(22) Filed: **May 24, 2021**

(51) LOC (14) Cl. **09-07**

(52) U.S. Cl.

USPC **D9/447**

(57) **CLAIM**

The ornamental design for a container insert, as shown and described.

DESCRIPTION

FIG. 1 is a top perspective view of a container insert;

FIG. 2 is a left-side view FIG. 1;

FIG. 3 is a right-side view of FIG. 1;

FIG. 4 is a back-side view of FIG. 1;

FIG. 5 is a front-side view of FIG. 1; and,

FIG. 6 is a top view of FIG. 1.

In the drawings, the broken lines show portions of a container insert that form no part of the claim.

1 Claim, 5 Drawing Sheets
